United States Patent

Des. 240,635
Patented July 20, 1976

240,635

HAND-HELD OPTICAL CODE SCANNER OR SIMILAR ARTICLE

Thomas A. Peterson, Dayton, Ohio, assignor to Monarch
Marking Systems, Inc., Dayton, Ohio

Filed Dec. 6, 1974, Ser. No. 530,256

Term of patent 14 years

Int. Cl. D14—02

U.S. Cl. D26—5 C

FIG-1

FIG-2

FIG-3

FIG-4

FIG-5

FIG-6

FIG-7

FIG. 1 is a right front perspective view of a hand-held optical code scanner or similar article showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom plan view thereof;

FIG. 7 is a top plan view thereof.

I claim:

The ornamental design of a hand-held optical code scanner or similar article, substantially as shown.
